UNITED STATES PATENT OFFICE.

EDWARD S. KELLEY, OF COLORADO SPRINGS, COLORADO.

DESIGN FOR A GAME-BOARD.

SPECIFICATION forming part of Design No. 30,640, dated April 25, 1899.

Application filed November 19, 1898. Serial No. 696,939. Term of patent 7 years.

To all whom it may concern:

Be it known that I, EDWARD S. KELLEY, a citizen of the United States, residing at Colorado Springs, in the county of El Paso and State of Colorado, have invented and produced a new and original Design for a Game-Board, of which the following is a specification.

My invention relates to a game-board, of which the accompanying drawing shows an illustration.

A is a square-shaped box or tray having a flat bottom with four sides extending around and projecting a little above the bottom. In the bottom are three cavities 1 2 3, arranged to occupy the three corners of a suppositious triangle located about in the center of the board, each cavity being differently colored.

I claim—

The design for a game-board as herein shown and described.

EDWARD S. KELLEY.
